UNITED STATES PATENT OFFICE

CECIL H. LAWRENCE, OF ATTLEBORO, MASSACHUSETTS, ASSIGNOR TO EVANS CASE COMPANY, OF NORTH ATTLEBORO, MASSACHUSETTS, A CORPORATION OF MASSACHUSETTS

DESIGN FOR A HAND MIRROR

Application filed January 16, 1933. Serial No. 46,860. Term of patent 3½ years.

To all whom it may concern:

Be it known that I, CECIL H. LAWRENCE, a citizen of the United States, and a resident of Attleboro, in the county of Bristol and State of Massachusetts, have invented a new, original, and ornamental Design for a Hand Mirror, of which the following is a specification, reference being had to the accompanying drawing, forming part thereof, in which

The lining in Figure 1 represents solid coloring but any color may be used. The edges and the ornamental features of the article are metallic. The design is applicable also to other toilet articles such as hair brushes.

I claim:

The ornamental design for a hand mirror, as shown and described.

In testimony whereof, I have signed my name to this specification this 10th day of January, 1933.

CECIL H. LAWRENCE.
